J. R. Littell

UNITED STATES PATENT OFFICE.

ANTHONY J. BATTLE, OF BROOKLYN, NEW YORK.

AUTOMATIC COAT-RACK.

SPECIFICATION forming part of Letters Patent No. 718,688, dated January 20, 1903.

Application filed November 7, 1901. Serial No. 81,464. (No model.)

To all whom it may concern:

Be it known that I, ANTHONY J. BATTLE, a citizen of the United States, residing at Brooklyn, in the county of Kings and State of New York, have invented certain new and useful Improvements in Automatic Coat-Racks, of which the following is a specification.

This invention relates to automatic coat-racks; and it has for its object to provide an improved device of this class in which the coat or other garment may be automatically locked in suspended position to prevent its extraction without the use of the proper key, which key is automatically released and deposited in a convenient receptacle when the coat is suspended from the device.

A further particular object of my invention consists in the provision of a device of this class which will be relatively simple and inexpensive in construction and positive and efficient in use.

In the drawings, Figure 1 is a vertical transverse sectional view of my improved automatic coat-rack, showing the parts in normal or inoperative position. Fig. 2 is a similar view showing the parts in operative position. Fig. 3 is a detail horizontal transverse sectional view taken upon the line $x-x$, Fig. 1, and looking downwardly.

Corresponding parts in all the figures are denoted by the same reference characters.

Referring to the drawings, 1 designates my improved automatic coat-rack, which embodies two relatively movable curved jaws or members, respectively—an upper member 2 and a lower member 3. These jaws are preferably arranged in the same vertical plane and project at their outer end portions 4 and 5, respectively, exteriorly of a hollow casing 6, and said jaws 2 and 3 project at their inner end portions 7 and 8, respectively, within said casing 6. The end portions 4 and 5 are arranged in opposed relation, as are also the end portions 7 and 8, the upper member 2 being curved upwardly and the lower member 3 being curved downwardly. The jaws 2 and 3 project, respectively, through openings 9 and 10, formed in the front plate 11 of the casing 6. The jaw 2 is limited in its movement through the opening 9 by means of contact with the jaw 3, with which it is arranged

to engage at both its inner and outer end portions, and the movement of the jaw 3 is limited by stop devices 12, which are preferably carried by the same, and consists of an inner shoulder 13 and an outer shoulder 14, which are formed upon the jaw 3 and are arranged for engagement, respectively, with the inner surface and the outer surface of the front plate 11 of the casing 6 as the jaw 3 slides through the opening 10. The coat is suspended from the lower jaw 3, at the outer end portion 5 of the same, and the weight of the coat causes said jaw 3 to slide inwardly through the opening 10 to an extent limited by the engagement of the shoulder 14 with the front plate 11 of the casing 6. Previous to this latter engagement, however, the inner end portion 8 of the jaw 3 engages with the inner end portion 7 of the jaw 2 and causes the latter jaw to slide outwardly through the opening 9 until the outer end portion 4 of the jaw 2 is brought into engagement with the coat which is suspended from the jaw 3 or simply into engagement with the outer end portion 75 of the jaw 3, and thus prevents extraction of the coat. To this end means 15 are provided for locking the jaw 2 in the operative position last described, and when the jaw 2 is locked in such position the jaw 3 is also locked 80 against movement by means of the shoulder 14, which is in engagement with the casing 6 and the jaw 2.

In the preferred form of construction the means 15 for locking the jaw 2 in operative 85 position consist of a pivoted detent or pawl 16, which operates at its lower end in connection with a plurality of serrations or corrugations 17, which are formed upon the upper surface of the jaw 2, and said detent is 90 so arranged when in operative position that it does not prevent projection of the jaw 2 through the opening 9, but prevents retraction of the same through said opening 9 in the casing 6. To this end the detent 16 is 95 pivotally connected with a locking mechanism 19, which is arranged within the casing 6 above the jaw 2 and is provided with a key 18, whereby the locking mechanism 19 may be operated to raise the pawl 16 out of engagement with the serrations 17. The detent 16 may rest normally in engagement with a

guide-pin 20, which maintains it in proper operative position for engagement with the serrations 17.

In the rear part of the casing 6 is arranged 5 a chute 21, which extends downwardly from the top of the casing 6, at which it opens at its upper end 22, and said chute 21 is curved at its lower end 23, whereby its lower orifice 24 projects above a tray or cup 25, which is 10 arranged conveniently at the front of the casing 6. The orifice 24 of the chute 21 may open through the front plate 11 of the casing. Through this chute 21 the key 18 is automatically delivered to the user of the coat-rack 15 when the coat is suspended from the lower jaw 3, causing said jaw to rise at its inner end portion 8. The key 18 is temporarily sustained within the chute 21 by a hinged bracket 26, which is carried by the inner end 20 portion 8 of the jaw 3 and normally projects transversely across and within the chute 21 through an opening 27, formed in the front wall of the chute 21. The bracket 26 is hinged to the inner end portion 8 of the jaw 25 3, as at 28, and may be normally sustained in horizontal position by the engagement of the same with the lower wall of the opening 27 in the chute 21 or may be so suspended in operative position by a spring 29, which bears 30 at one end upon the lower side of the bracket 26 and at the other end upon the inner end portion of the jaw 3. The key, which is initially deposited in the chute 21 at the upper end or orifice 22 of the same, normally rests 35 upon the bracket 26; but when the outer end portion 5 of the jaw 3 is depressed by the weight of a coat suspended from the same and the inner end portion 8 of the jaw 3 is simultaneously elevated the upper side of the bracket 40 26 engages with the lower end of a finger 26^a, the upper end of which is secured above the opening 27 in the chute 21, thus causing the pivotal depression of the bracket 26 within the chute 21 and permitting the key 18 to pass 45 downwardly within the chute 21 and to exit from the same at the lower orifice 24 of the chute, at which point it enters the tray or cup 25. The key is taken from the tray or cup and kept by the user of the coat-rack until he desire 50 to unlock the upper jaw 2 and extract his coat from between the outer end portions 4 and 5 of the jaws, at which time he inserts the key into the locking mechanism 19 and elevates the detent 16 from its position of engagement with the serrations 17.

It will be understood that the end portions 4 and 5 and the end portions 7 and 8 of the jaws 2 and 3 are sufficiently spaced apart to permit of the relative movement of said jaws 60 sufficient to allow the introduction of a coat between the outer end portions 4 and 5 of said jaws, and the lower jaw 3 is preferably weighted at its inner end portion 8, as at 30, to maintain the outer end portion 5 of the 65 same in position of full projection. The inner end portion 7 of the upper jaw 2 is also preferably weighted, as at 31, to normally

maintain said jaw in the position of full retraction. This weighting of the lower jaw 3 insures the maintenance of the same in proper 70 position to sustain the bracket 26 in operative position to support the key 18, and the weighting of the inner end of the jaw 2 maintains the same in proper position to provide the necessary space between the outer end 75 portions 4 and 5 of the jaws 2 and 3 for the introduction of the coat between said jaws.

The operation and advantages of my improved automatic coat-rack will be readily understood.

With the parts in the position shown in Fig. 1 a person desiring to use the coat-rack suspends a coat from the end portion 5 of the lower jaw 3 by means of the collar or hanger of the same, as shown in dotted lines in Fig. 85 2, and said outer end portion 5 of the jaw 3 is immediately lowered by the weight of the coat, causing the elevation of the inner end portion 8 of the jaw 3, which inner end portion engages with the inner end portion of 90 the jaw 2 and tilts the same outwardly, so that the outer end portion of the jaw 2 comes into engagement with the coat or with the outer end portion 5 of the jaw 3 and locks the same against extraction. Simultaneously the 95 bracket 26 is folded downwardly within the chute 21 and the key 18 for the locking means 19 falls into the tray or cup 25, whence it is taken by the user of the coat-rack and retained by him until such time as he shall desire to release the jaw 2 from the locking means 19, which is accomplished by inserting the key 18 into the said locking means 19 and raising the detent 16 from the serrations 100 17. The jaw 2 may then be slid inwardly of the casing 6 to relatively separate the outer end portion 4 of the jaw 2 from the outer end portion 5 of the jaw 3 and permit the extraction of the coat from said jaws. The weighted portion 30 of the jaw 3 will then lower the inner end portion 8 of the jaw 3 and cause the bracket 26 to project into operative position to receive and sustain the key, which is subsequently deposited in the chute 21 at the upper end of the same after said key has been 115 removed from the locking means 19, which have been manipulated to cause the detent 16 to descend into operative position with respect to the serrations 17.

The entire device is relatively simple in 120 construction and operates effectively to prevent malicious removal of a garment or garments suspended from the same. The casing 6 may be ornamental in appearance and may be conveniently installed in public buildings—such as hotels, theaters, and similar places—or in private hallways or living-rooms. The device is extremely neat in appearance, the casing 6 inclosing all of the operative parts of the same with the exception 125 130 of the two projecting jaws 2 and 3.

I do not desire to be understood as limiting myself to the details of construction and arrangement as herein described and illustrated,

as it is manifest that variations and modifications may be made in the features of construction and arrangement in the adaptation of the device to various conditions of use without departing from the spirit and scope of my invention and improvements. I therefore reserve the right to all such variation and modification as properly falls within the scope of my invention and the terms of the following claims.

Having thus described my invention, I claim and desire to secure by Letters Patent—

1. An automatic coat-rack, comprising a casing having its front formed with an upper and a lower opening, an upper curved jaw extending through said upper opening, and having a sliding and a pivotal movement on the lower wall thereof, and a lower curved jaw extending through said lower opening, and having its inner end in contact with the inner end of the upper jaw.

2. An automatic coat-rack, comprising a casing having its front formed with an upper and a lower opening, an upper curved jaw extending through said upper opening and weighted at its inner end, and having both a sliding and a pivotal movement on the lower wall of the upper opening, and a lower curved jaw extending through the lower opening and having its inner end in contact with the weighted end of the upper jaw.

3. An automatic coat-rack, comprising a casing having its front formed with an upper and a lower opening, an upper curved weighted jaw extending through said upper opening, and having both a sliding and a pivotal movement on the lower wall of said opening, a lower curved arm extending through said lower opening, and having its inner end in contact with the weighted end of the upper jaw, and means for locking the upper jaw.

4. An improved automatic coat-rack, comprising two relatively movable jaws, a casing in which said jaws are mounted, locking means whereby said jaws may be secured in operative position, a key-delivery chute arranged within said casing and provided at one side with an opening, and key-delivery devices operatively connected with one of said jaws and projecting through said opening and whereby a key adapted to said locking mechanism may be sustained against delivery when said chute is in normal position and from which said key may be released when said jaw is moved into operative position.

5. An improved automatic coat-rack of the class described, comprising two relatively movable jaws, means for locking said jaws in operative position, a casing in which said jaws are mounted, a key-delivery chute arranged within said casing, a key-delivery device operatively connected with one of said jaws and whereby a key adapted to said locking mechanism may be sustained against delivery within said chute, said key-delivery devices consisting of a bracket which is hinged to one of said jaws and projects through an opening in one side of said chute, and means for depressing said bracket to release the key, when the jaw carrying the bracket is moved into operative position.

6. An automatic coat-rack, comprising a casing formed at its front with an upper and a lower opening, two oppositely-curved jaws extending one through each of said openings, so that their inner ends contact, and the upper one of said jaws having both a sliding and a tilting movement, means for locking the upper jaw, and stops for limiting the movement of the lower jaw.

7. An automatic coat-rack comprising a casing formed at its front with an upper and a lower opening, a pair of oppositely-curved jaws extending respectively, one through each of said openings, and having their inner ends in contact, the upper one of said jaws having both a sliding and a tilting movement on the lower wall of the opening through which it extends, stops for limiting the movement of the lower jaw, and a locking device for securing the upper jaw in its forward position.

8. An automatic coat-rack, comprising a casing formed at its front with an upper and a lower opening, a pair of oppositely-curved jaws extending respectively one through each of said openings, and having their inner ends in contact, the upper one of said jaws being weighted at its inner end, and having both a sliding and a tilting movement on the lower wall of the opening through which it extends, a pawl-and-ratchet device for locking the upper jaw, and means for limiting the movement of the lower jaw.

In testimony whereof I have signed my name in the presence of the subscribing witnesses.

ANTHONY J. BATTLE.
